ERNEST G. RIDER, OF PHILADELPHIA, PENNSYLVANIA, ASSIGNOR TO STOKES & SMITH COMPANY, OF SUMMERDALE, PENNSYLVANIA, A CORPORATION OF PENNSYLVANIA.

BOX-SHELL-FEEDING MEANS FOR BOX-COVERING MACHINES.

1,295,602.

Specification of Letters Patent. Patented Feb. 25, 1919.

Application filed November 15, 1916. Serial No. 131,444.

To all whom it may concern:

Be it known that I, ERNEST G. RIDER, a citizen of the United States, residing at 419 N. E. Boulevard, Philadelphia, in the county of Philadelphia and State of Pennsylvania, have invented certain new and useful Improvements in Box-Shell-Feeding Means for Box-Covering Machines, of which the following is a specification.

My present invention relates generally to box covering machines of that type wherein a covering sheet or blank is folded about the outer walls of a box-shell and secured thereto by adhesive, and more particularly the invention relates to a means for automatically feeding the box-shells or blanks to be covered directly into the machine.

The box-shell feeding means of the present invention is especially applicable to box-covering machines of that type wherein a box-form is employed for carrying the box-shell together with its covering blank or wrapper into coöperative association with the instrumentalities for folding the covering blank or wrapper about the outer walls of the box-shell and affixing the same thereto by adhesive, such for instance as the covering machines shown and described in Patents Nos. 691,329 dated January 14th, 1902; 778,805 dated December 27th, 1904; and 912,745 and 912,746 dated December 16th, 1909, although it is to be understood that the box-shell feeding means referred to may be employed in connection with any type of covering mechanism wherein a box-form is employed to carry the box-shell to be covered into coöperative association with the cover applying instrumentalities, the present showing and application of the invention being merely by way of illustration.

In box covering machines of the type referred to, it has been the practice heretofore to place the box-shells upon the box-form by hand, although it has been proposed in some instances to feed the box-shells into the machine in position to be entered by the box-form during the movement of the latter toward the cover-applying instrumentalities. The first mentioned method, namely, that of placing the box-shells upon the box-form by hand, is not entirely satisfactory, because such operation is somewhat slow and tedious, and therefore reduces the output of the machine, and is further open to the objection that accidents are likely to occur to the

hands of the operator during the application of the box-shells to the box-form, especially if the operators are careless or inexperienced. The second named method has not proved to be satisfactory because of the difficulty of properly centering and maintaining the box-shells in an accurately registered position below the box-form so that the latter will always enter the box-shell without engaging and thereby breaking a wall or 60 walls thereof.

According to the present invention, I provide means for feeding the box-shells into the machine, and for placing or fitting them directly upon the box-form, the said box-shell feeding means being preferably operated from a moving part of the box-covering machine and operative in timed relation with the movements of the box-form so that the operations of feeding and covering the box-shells may be performed automatically and in timed relation one with the other, to the end that the daily output of the machine will be materially increased.

Broadly and generally stated, the invention comprises in combination, a box-form, and means for automatically placing or fitting a box-shell thereupon.

More specifically stated, the invention embodies, in combination, a movable box-form for supporting a box to be covered, cover applying instrumentalities into which the said form is adapted to carry the box-shell and its covering wrapper to have the latter applied thereto, and means for bodily transporting the box-shell toward the box-form with a wall of the shell in position to engage a wall of the form in such a way that when the wall of the shell engages the wall of the form, the shell will be moved directly upon the form automatically and without the aid of hand operation.

In order to enable others skilled in the art to understand, construct and use my said invention, I will now proceed to describe one embodiment thereof in detail, reference being had for this purpose to the accompanying drawings, wherein,

Figure 1 is a side elevation of a portion of a known form of box covering machine having my improved box-shell feeding means associated therewith.

Fig. 2 is a plan view of the same.

Fig. 3 is a rear elevation of the box-supporting and advancing means.

Fig. 4 is an enlarged view showing a box-shell supported between the box supporting members or blocks.

Fig. 5 is a perspective view of one of the 5 box-supporting members or blocks.

Fig. 6 is a similar view looking at the opposite face of the block from that illustrated in Fig. 5.

Fig. 7 is a vertical sectional view taken 10 through one of the blocks to show the yielding means for engaging a wall of the box-shell.

Fig. 8 is an inverted transverse section taken on the line 8—8, Fig. 6.

15 Fig. 9 is a side elevation partly in section showing the manner of supporting an unstayed box-shell.

Fig. 10 is a side elevation showing the 20 relative positions of the box-form and box-shell during advancing movement of the latter and just prior to the entering of the shell onto the form.

Fig. 11 is a similar view showing the 25 position of the parts after assembly and just prior to the lifting of the box-shell onto the form.

Fig. 12 is a side elevation showing the box-shell fitted to the box form.

Fig. 13 is a view of the box-form showing 30 how the box-shell retaining clips hold the shell thereupon.

My improved box-feeding means may be 35 associated with any preferred type of covering machine wherein a box-form for supporting the box-shell is employed, and I wish it understood that the present showing is only by way of example and not intended 40 to be in the nature of a limitation.

In the particular type of covering machine illustrated in Fig. 1, there is embodied 45 among other mechanisms, a vertically reciprocating box-form *a*, which may be of any desired construction and configuration, depending upon the type of box to be 50 covered, the said form being adapted to support and carry the box-shell *x* into coöperative association with suitable cover or wrapper applying instrumentalities. The latter, in the instance shown, may consist 55 of two pairs of spaced apart covering applying rollers *b*, *b'*, one pair, *b'*, being arranged below and at right angles to the other; two pairs of end-lap turn-in wings *c* located between the two pairs of cover applying rollers, and two pairs of edge tuck-in blades or fingers *d*, located below the lower pair of rollers *b'*, the said blades or fingers operating to tuck the marginal edges of the covering blank or wrapper over the 60 upper edge of the side walls of the box-shell as is well understood in the art. The machine also embodies a movable platen *e*, with which the box-form *a*, coöperates, these two members operating to clamp the box-shell with its covering blank or wrapper

therebetween and carry the same through the cover applying instrumentalities to have the covering wrapper or blank applied to the outer walls of the box-shell.

My improved box-shell feeding means 70 operates to successively transport the box-shells *x*, bodily from a position at one side of the box-form *a*, as shown in Fig. 10, to and place them directly upon the said form preferably when the latter is at rest as 75 shown in full lines in Fig. 12. To accomplish this, the box-shells are successively advanced toward the box-form *a*, open end up, but with their bottom and side walls canted or inclined relative to the bottom 80 and side walls of the box-form, the said advancing movement continuing until the box-shell is brought directly under the box-form with one end of the latter extending into one end of the shell and a canted side-wall of the shell in engagement with a side wall of the form, whereupon continued relative movement between the parts causes the canted shell to be lifted bodily and automatically directly upon the form, as more 85 clearly shown in full lines in Fig. 12, after which the form descends carrying its box-shell first into contact with the platen *e*, upon which the covering blank has been placed and then through the several cover 90 applying instrumentalities for the stated purpose, the several cover applying steps or operations being then performed by suitable mechanism, such for instance, as that illustrated more or less conventionally in 10 Fig. 1.

Any preferred means may be employed 10 for supporting and advancing the box-shell in an inclined or canted position toward the box-form to bring about the described operations and obtain the stated objects, but I prefer to provide a construction that will permit of a bodily pivotal or upwardly swinging movement of the box-shell immediately a canted or inclined side wall of 15 the box-shell engages a side wall of the box-form.

The box-shell supporting and advancing means according to the present embodiment of the invention consists of two spaced apart 20 members shown in the form of blocks 20, between which an end of the box-shell *x* is placed by hand, the said members or blocks being spaced apart a distance corresponding substantially to the width of the box-shell 25 to be covered and operating to support the latter in such a way that the lower canted end of the box-shell will be free to swing upwardly in a pivotal manner. Preferably the adjacent faces of the respective blocks 30 are provided with yielding means for engaging the opposite side walls of the box-shell, said yielding means in the instance shown consisting of balls or rollers 21 normally urged outward by means of springs 22, as 35

more clearly shown in Fig. 7. The yielding balls or rollers constitute a means for supporting the box-shell in such a way that the shell may readily move or swing bodily relative to the supporting members or blocks.

Each block is preferably provided on that face carrying the balls or rollers 21 with a combined box rest and lifting member shown 10 in the present instance in the form of a plate 23, pivoted at 24 to the block 20. A spring 25, Fig. 6, connected at one end to the pivot 24 of the plate and at its other end to a part of the block 20 serves to normally maintain 15 the front edge 26 of the plate in proper position relative to the block to support the box-shell in a normally inclined or canted position and to permit of a swinging movement of the plate on its pivot to effect a 20 bodily lifting movement of the box-shell at the proper time, as when a wall of the box engages a wall of the box-form, all as will hereinafter more clearly appear.

As shown in Fig. 4, the box-shell α when 25 in proper position between the supporting members or blocks, is engaged on two opposite faces or walls by the said blocks while a rear face or wall rests against and is supported adjacent the corners of the shell by 30 the pivoted lifting plates 23.

Any suitable means may be employed for carrying and advancing the box supporting members or blocks in order to carry the box-shell supported thereby into coöperative relation with the box-form α . In the present embodiment of the invention I have shown this means as consisting of a reciprocating carriage 27 moving between parallel guides 28 supported upon a part of the machine 35 frame. The carriage is provided with a standard 29, upon which is adjustably mounted a block 30 having outwardly extending arms 31 upon each of which is mounted a bar 32 each carrying one of the blocks 20, the bars 32 being adjustable to 40 toward and from each other upon the arms 31, as more clearly shown in Fig. 2, this adjustment being provided to adapt the box-shell supporting members or blocks for use in connection with box-shells of different sizes.

The carriage 27 may be reciprocated toward and from the path of movement of the box-form α , by any suitable means, which means in the instance shown, consists of a 45 lever 33 having a link connection 34 with the carriage 27, the lever being oscillated about its pivot 35 by means of a link 36 connected to a pivoted arm 37, which arm is actuated by means of a cam 38 mounted upon a 50 driven shaft 39 of the machine. A spring 40 is connected to the lever 33 in such a way as to normally maintain the carriage 27 in its retracted position, or in the position shown in Figs. 1 and 2, which is the box- 55 shell receiving position.

I prefer to provide means associated with the box-shell supporting members or blocks upon which the bottom of the box-shell may rest when placed between the said supporting members or blocks, in order to initially 70 hold and support the box-shell in an inclined or canted position relative to the box-form α , in order to carry out the objects of the invention. This means may be of any preferred construction. In the instance shown, 75 it consists of two fixed inclined supporting fingers 41, each carried by a head 42 adjustably mounted upon a standard 43, which standards extend upward from a part of the machine frame, as more clearly shown in 80 Figs. 1 and 2. The box supporting fingers 41 are adjustable to accommodate boxes of different depths.

In the operation of the machine assuming the parts to be in the position illustrated 85 in Fig. 1, a box-shell to be covered is placed by hand between the box supporting members or blocks 20 with the bottom of the box resting upon the box-shell supporting fingers 41. When properly positioned the box- 90 shell will be supported in an inclined or canted position as more clearly shown in Figs. 1 and 10, the lowermost edge of the box-shell being disposed in a plane slightly below the plane of the under face of the box- 95 form α , so that when the box-shell is advanced toward the box-form the said lower edge of the box-shell will come right under the box-form with one side or end of the form gradually entering the box-shell during 100 the advancing movement of the latter until the parts assume the position illustrated in Fig. 11. When this position is reached a canted or inclined side wall of the box-shell will engage a vertical side wall of 105 the box-form and further relative movement between the parts, as for instance further movement of the shell toward the form will, by reason of the walls contacting as described, cause a bodily lifting movement to be imparted to the box-shell so as to lift it directly upon the box-form, and this action is assisted by reason of the swinging movement 110 which will be imparted by the pivoted box-shell lifting plates 23 carried by the box 115 supporting members or blocks. When properly fitted upon the box-form the shell will be retained thereon during the movement thereof, by means of suitably constructed 120 clips α' , Figs. 1 and 13.

The box shell having been properly placed upon the box-form as described, the form with this box thereon now descends and is brought into engagement with the body-portion of a box covering blank, which has 125 been previously placed upon the platen e . The box with its covering blank is then carried through the first pair of covering rollers b , which operate to apply the covering blank to two side walls of the box, after which the 130

- two pairs of end-lap turn-in wings *c*, operate to turn in and apply the projecting end-laps of the blank against the end walls of the box. The thus partially covered box is then carried between the two covering rollers *b'*, to apply the remaining portions of the covering blank to the remaining uncovered walls of the box, after which the upstanding marginal edges of the blank are turned over the upper edges of the box-shell by means such as fingers *d*, and such edges are finally turned downward into and secured to the inner walls of the box-shell to completely cover and produce the finished box.
- 15 It is to be understood of course that the cover applying instrumentalities for affixing the cover blank to the box, as well as the operative sequence of these parts as herein described, are merely illustrative, and that my improved box-shell feeding means may be associated with box-covering machines having a different sequence of operations, the showing herein made being only by way of illustration.
- 25 The term "box-shell" as herein employed, is used in its broad sense to include a shell that is "stayed" at its corners as well as a shell that is "unstayed," as the box-supporting and advancing means of the present invention will operate to support and carry a box-shell whether stayed or unstayed. In order to illustrate this, I have shown in Fig. 9 how an unstayed box-shell will appear when placed between the supporting members or blocks 20, the box-shell in this figure being designated by the letters *xx*.
- I do not wish to be understood as limiting myself to the particular mechanism herein shown and described for automatically applying the box-shells directly to the form block of a covering machine, as I am well aware that other means may be employed for accomplishing the stated object, without departing from the spirit of the invention.
- 45 What I claim is—
1. In a box covering machine, and in combination, a movable box-form for supporting a box to be covered, cover applying instrumentalities into which the said form is adapted to carry the box and its covering wrapper to have the latter applied thereto, a movable box-shell feeding device constructed to support and carry a box-shell in a canted position to be entered by the said box-form, and means for moving the said feeding device to and from the path of movement of the box-form, the advancing movement operating to bring a canted wall of the box-shell into contact with a wall of the plunger whereby to impart a bodily lifting movement to the box-shell to automatically place it upon the box form.
  2. In a box covering machine, and in combination, a movable box-form for supporting a box to be covered, cover applying in-

strumentalities into which the said form is adapted to carry the box and its covering wrapper to have the latter applied thereto, and means for supporting and bodily transporting a box-shell toward the box-form 70 with a canted side wall of the shell in position to engage a side wall of the form after the latter has partially entered the shell whereby engagement of the parts operates to impart a bodily lifting movement to the 75 shell to automatically place it upon the form.

3. In a box covering machine and in combination, a box-form, a box-shell freely supporting means for supporting a box-shell in an inclined or canted position relative to the 80 box-form, means for effecting a relative approaching movement between the said form and supporting means to cause the form to enter the box-shell and a canted or inclined wall of the box-shell to engage a vertical 85 wall of the form and thereby lift the shell bodily onto the form.

4. In a box covering machine and in combination, a vertically reciprocating box form, and box shell supporting and carrying means 90 having a movement of translation intersecting the path of movement of the box form for carrying and automatically placing a box-shell onto the box form during such translating movement.

5. In a box covering machine and in combination, a movable box form, box-shell supporting means for supporting a box in an inclined or canted position, and mechanism for imparting a movement of translation to 100 said supporting means for effecting a feeding movement of the box-shell into the path of movement of the box form whereby a canted wall of the box-shell will be brought into contact with a wall of the box form and the shell thereby lifted bodily onto the form.

6. In a box covering machine and in combination, a vertically reciprocating box form, a box-shell supporting and feeding means for supporting an open box-shell in an inclined or canted position, and mechanism for advancing the supporting means to carry the canted box-shell to a position beneath the box form and a canted inner wall of the box-shell into engagement with a vertical 110 wall of the box form whereby the box-shell will be lifted automatically onto the box form.

7. In a box covering machine, and in combination, a box-form, and box-shell feeding 120 means for supporting and advancing a box-shell to and for placing the same directly upon the form, said means embodying a pair of spaced apart members between which the box-shell is freely supported, for bodily tilting movement relative to said members and from between which members the shell may be moved by the box form.

8. In a box covering machine and in combination, a box-form, movable means for 130

- freely supporting a box-shell with side walls thereof in an inclined or canted position with relation to the side walls of the form, means for advancing the supporting means and 5 box-shell toward the form so that a portion of the latter will enter the box, and means acting upon a canted wall of the box for thereafter swinging the canted box to place it directly onto the form.
- 10 9. In a box covering machine and in combination, a box-form and a box-shell supporting means therefor, embodying a pair of oppositely disposed spaced apart members having yielding faces for yieldingly embracing 15 the opposite walls of a canted or inclined box to permit free bodily swinging movement of the box-shell relative to said members, and means for moving said members toward and from the box form.
- 20 10. In a box covering machine, and in combination, a box-form, means for supporting and advancing a box-shell in a canted or inclined position toward the form, embodying spaced apart members for embracing opposite walls of the box and between 25 which the box may have a pivotal movement, and means operative upon an exterior wall of the box between the said embraced walls for imparting a bodily lifting movement to the box to place the same directly 30 upon the form.
11. In a box covering machine, and in combination, a vertically reciprocating box form, a box-shell advancing and supporting means for supporting and advancing a canted box-shell and for placing it directly 35 upon the form, said means embodying a pair of oppositely arranged spaced-apart members for embracing opposite side walls of the box-shell and from between which the latter may be moved, and means for advancing and retracting said spaced-apart members toward and from the box form in a 40 plane intersecting and at right angles to the path of movement thereof.
- 45 12. In a box covering machine and in combination, a vertically reciprocating box form, a box-shell supporting and feeding means for supporting an open box-shell in an inclined 50 or canted position, said means permitting tilting or swinging movement of the box-shell relative to and independently of its supporting means, and mechanism for causing the supporting means to carry the canted 55 box-shell to a position beneath the box form and a canted inner wall of the box-shell into engagement with a vertical wall of the box form whereby the box-shell will be lifted bodily onto the box form.
13. In a box covering machine and in combination, a box form for supporting and carrying a box to be covered, box supporting and advancing means for transporting a box-shell to and for placing it upon the box-form, said means embodying a pair of adjustably mounted spaced-apart members for embracing opposite walls of the box-shell and a pivoted plate carried by each member for engaging an external wall of the box-shell to impart a bodily lifting movement to the box-shell to place it directly onto the box form.
14. In a box covering machine, and in combination, a box-form for supporting and carrying a box to be covered, means for supporting a box-shell in an inclined or canted position relative to the box-form, means for reciprocating the said box-supporting means toward and from the box-form, and stationary means constituting a support for the bottom of the box-shell when resting between the supporting means.
15. In a box covering machine, and in combination, a box-form for supporting and carrying a box to be covered, and box feeding means for feeding boxes into the machine and for placing them directly upon the box-form, said feeding means embodying a reciprocating member movable toward and from the path of movement of the box-form, and a pair of laterally adjustable spaced apart box-supporting members carried by the reciprocating member and between which the box-shell to be covered may be removably sustained.
16. In a box covering machine and in combination, a vertically reciprocating box-form for supporting and carrying a box-shell to be covered, a box-shell feeding means comprising a pair of spaced apart blocks for embracing opposite side walls of a box-shell and for supporting said box-shell in an inclined or canted position relative to the box-form, a pivoted plate carried by each of the said blocks for engaging a wall of the box-shell between the said embraced walls and for imparting a bodily swinging or pivotal movement to the box-shell, and means for advancing the said blocks toward the box-form to cause an end of the latter to enter the box-shell at one end thereof.

In testimony whereof I affix my signature in the presence of two witnesses.

ERNEST G. RIDER.
